UNITED STATES PATENT OFFICE

JOHN C. HAGGART, JR., OF ALMA, MICHIGAN, ASSIGNOR TO REPUBLIC TRUCK SALES CORPORATION, OF ALMA, MICHIGAN, A CORPORATION OF MICHIGAN

TRACTOR SHOE

Application filed January 9, 1928. Serial No. 245,293.

The present invention pertains to a novel tractor shoe designed particularly for use in the assembly of the endless or track laying tread members for tractors.

It is an object of the invention to provide a tractor shoe which will prevent the driving thrusts from being transmitted through metal-to-metal contacts to the driving shafts or framework and to absorb these thrusts as near as possible to the ground. In the accomplishment of this object, the shoe is constructed of upper and lower sections with a resilient pad inserted therebetween. The pad is connected independently to the two sections; in other words the securing members binding the pad to one of the sections are not connected to the other section. In this manner there is provided a yielding or elastic connection between the lower ground-engaging section and the upper section of the shoe, and this form of connection assists in taking the driving thrusts.

The invention is fully disclosed by way of example in the following description and in the accompanying drawing, in which—

Figure 1 is a plan view of a number of shoes connected together; and

Fig. 2 is a longitudinal section of one of the shoes on the line 2—2 of Figure 1.

Reference to these views will now be made by use of like characters which are employed to designate corresponding parts throughout.

As already indicated, the shoe comprises an upper section 1 and a lower or ground-engaging section 2, between which is interposed a resilient pad 3. At the transverse edges of the upper section are provided rows of bolts 4 which bind this section to the pad and have their lower ends seated in recesses 5 in the lower section 2. The lower ends of the bolts are fitted with nuts 6 received in the recesses for preventing slipping of the bolts. It will be seen that the nuts are received loosely in their respective recesses in order to

45 avoid contact of the nut with the metal parts of the shoe, as a result of which there is no interference with the resilient action of the pad 3. The bolts 4 are alternated with recesses 7 formed through the upper section, and these recesses receive the heads 8 of bolts 9

which pass through the pad 3 and are anchored in the lower section 2.

It will now be apparent that the intermediate pad 3 is connected alternately or independently to the two sections, the binding members securing one of the sections to the pad being entirely free of the remaining section so that there is no rigid or metallic contact between the two sections of the shoe.

The upper section 1 is formed with a marginal rib 10 on its lower surface for engaging the edge of the inner pad and further holding the same against slipping. A rib 11 is formed transversely of the lower section 2, extending upwardly into the bottom of the pad for preventing too great a slip between the upper and lower sections and to avoid taxing the elasticity of the pad 3 and excessive shearing action at the bolts 4 and 9.

The lower member 2 is formed with a tread member 12 in the form of a V-shaped rib on its lower surface. The transverse edges are formed with knuckles 13 for insertion between and alignment with similar knuckles on the adjacent shoes, whereby the tractor chain may be assembled by pivot bolts 14 passed through such aligned knuckles.

Due to the elastic connection between the ground-engaging section 2 and the upper section 1, the driving thrusts are somewhat absorbed before reaching the upper section and other parts of the tractor, as contemplated in the object of the invention.

Although a specific embodiment of the invention has been illustrated and described, it will be understood that various alterations in the details of construction may be made without departing from the scope of the invention as indicated by the appended claims.

What I claim is:—

1. In a tractor shoe, a substantially flat upper section, a substantially flat lower section, a resilient pad inserted between said sections, binding members securing the pad to the upper section and free from the lower section, and similar members securing the pad to the lower section and free from the upper section.

2. In a tractor shoe, a substantially flat upper section, a substantially flat lower sec-

tion, a resilient pad inserted between said sections, binding members securing the pad to the upper section and free from the lower section, similar members securing the pad to the lower section and free from the upper section, and a transverse rib extending from one of said sections into the pad.

5 In testimony whereof I affix my signature.

10 JOHN C. HAGGART, JR.
